UNITED STATES PATENT OFFICE

CHARLES MARIUS MOTTE, OF PARIS, FRANCE

HYDRAULICALLY PROPELLED LIFEBOAT

Application filed March 6, 1931, Serial No. 520,646, and in France March 6, 1930. Renewed May 4, 1932.

Improved life boats actually in use are of two types, the first type is propelled by oars, and the second type is propelled by one or more internal combustion engines with, as propelling means, one or two screw propellers, preferably arranged under housings.

Although these two types of boats have proved to be of great robustness and hold the sea well, they still do not allow to ensure the complete security desired by the International Life-Saving Societies. The conditions of security depend only on the accuracy of the members used which are too often paralyzed, either by shocks, cordage, or by drifting floating bodies, fatally exposing the rescuers to the mercy of the elements, notwithstanding their devotion and heroism.

This explains all the efforts made by all the great international organizations for discovering new improvements capable of improving the means used, but it is to be noted that all the researches made have been limited to known forms of parts, which condition renders nearly impossible the provision of means allowing to overcome the difficulties of security.

The present invention relates to a new water-tight life boat, adapted to remedy all the difficulties above mentioned, while ensuring to the crew and ship-wrecked persons the maximum security.

Its main qualities are:

- 1.—Great stability on the roughest sea,
- 2.—Water-tightness and unsubmersibility.
- 3.—Great robustness owing to its shape.
- 4.—An unknown navigability and security,
- 5.—A high carrying capacity.
- 6.—A small draft.

A form of carrying out the invention is illustrated, by way of example, in the accompanying drawing, in which:

Fig. 1 is a perspective view of a life boat in use.

Fig. 2 is a side view of the same life boat at rest.

Fig. 3 is a corresponding plan view thereof.

Fig. 4 is a front end view of the said life boat.

Fig. 5 is a rear end view of the life boat.

Fig. 6 is an underside plan view thereof.

Fig. 7 is a cross vertical section made according to line A—A of Fig. 2.

Fig. 8 is a longitudinal vertical section.

As illustrated in the drawing, the hull of the life boat is constituted by a sheet metal body 1, of uniform thickness, in the shape of a frustum of circular cross-section, terminating at its front end in a half-spherical compartment 2, and at its other end, in a second half-spherical compartment 3. This hull has a double wall, on its lower part, as shown in Fig. 7, and is stayed or braced throughout its length to constitute a fluid-tight compartment in case of damage at any point of the lower portion of the hull.

This hull is moreover so shaped as to present in its upper plane three curved transverse channels 4, 5 and 6, and, between the front channel 4 and the middle channel 5, a chamber 7, the upper horizontal wall of which is constituted by a water-tight panel 8.

A bridge 9 supported by uprights 10, leads to the panel 8 of the chamber 7, and a ladder 11 allows to have access to the bridge 9 from the poop of the boat.

A tubular mast 12 is pivoted on the chamber 7, so that it can be laid down on the bridge 9 and held in its normal vertical position by suitably arranged shrouds 13.

This life boat is provided with two pilots' cockpits: one 14, at the exterior, located at the bow in a cavity of suitable shape of the hull, adapted to isolate the man at the wheel and to also shelter the entrance to the watertight doors 15, which allow the pilot to enter

the hull for fulfilling the same function within the boat at the second pilot's cockpit.

The hull thus constituted, is entirely made of metal, completely water-tight and is provided with port-holes 16.

A horizontal stabilizing plane 17 acting at the same time as an anti-rolling plane, is secured on the outer wall of the hull, at the level of the water line.

10 Three other vertical planes 18, secured on the front half-spherical compartment, constitute fenders against shocks, and can, if need be, form supports for removable parts, such as wheels or caterpillars, so that the boat can move and enter the water by itself.

The hull is internally divided, by means of bulkheads, into four water-tight compartments 19, 20, 21 and 22 which can communicate with each other through water-tight doors 23, 24 and 25. The first compartment 19, located at the bow and to which the pilot has access through one of the doors 15, encloses the second pilot's cockpit 26, allowing to ensure steering from the interior of the boat and to shelter a part of the crew for the distance to be covered for reaching the place of the wreck. The second compartment 20 constitutes the engine-room, to which access may be had through the panel 8 or through the doors 15. The third compartment 21 can be reserved for the crew and the persons rescued, as well as the fourth compartment 22 which, moreover, constitutes a store-room for food and life-saving appliances. Access may be had to these three compartments 20, 21 and 22 either through the ladder 27, when coming from the bridge 9 and by opening the water-tight panel 8, or by opening a second panel 28 which closes an opening to which leads, in the compartment 22, a staircase 29.

40 The people rescued who have entered the life boat through the stern, but who are unable to ascend to the bridge, can reach the panel 28 by following the stepped passage 30 provided on the inclined wall of the hull, and enter the compartment 21 through the door 25.

45 The driving power is supplied by two heavy oil or gasoline engines 30', adapted to drive the turbines of hydraulic propelling units 30 and 31, having a fixed casing. These propelling units are two in number (Fig. 6) and are arranged on either side of the longitudinal axis of the boat, being placed in recesses provided in the bottom of the hull and supplied through a central water intake 32. These propelling units, provided with blades, allow to ensure forward and backward running, by causing the positions of the blades to vary through driving members independent from the engines.

50 A third propelling unit 33, having a vertical axis and an adjustable casing is arranged within the hull and in the middle por-

tion of the same; it allows to ensure changes of direction without a rudder. The life boat can however be provided with two emergency rudders 34 (Fig. 3).

55 Finally, the tubular mast used, is preferably provided with an electric lighting device comprising a headlight 35 projecting the light rays in front of the boat and a circular series of lamps with a reflector 36, lighting the bridge 9 and the whole of the boat.

75 From the foregoing the important advantages and high degree of safety of the present life boat thus devised will be easily understood.

80 Owing to its shape, it offers the minimum head resistance and it cannot capsize.

85 Its stability is automatically ensured by its shape and by the combination of its stabilizing planes which extend to the stern and of its fender planes arranged at the bow, the centre of buoyancy and the centre of gravity rigorously passing through the same point.

90 As far as the capsizing effects by side thrusts are concerned, they are annihilated by the curved transverse channels offering a high resistance.

95 The general arrangement of this shape of hull completely water-tight, allows the rescuers to take the sea whilst being in the interior of the boat, the latter being provided with a double steering wheel. When the life boat has reached the place of the wreck, the pilot returns to the outer steering wheel and the crew stand on the bridge and on the transverse channels.

100 Owing to the shape of the boat, its water line is within arm-length and the shipwrecked people can be rescued without great effort and with less risk than on usual boats.

105 Finally the tubular mast can ensure circulation of the air in the compartments and evacuation of the gases from the engine-room; it can moreover carry aerials for wireless apparatus.

110 It is to be understood that the life boat illustrated is given by way of example only and that the dimensions, details of construction, method of propulsion and accessories can be varied without departing thereby from the principle of the invention.

115 What I claim as my invention and desire to secure by Letters Patent is:

120 1. A life boat comprising a hull entirely made of metal, completely water-tight and in the shape of a frustum of circular cross-section, half-spherical compartments at the bow and stern respectively, three curved transverse channels on the upper plane of this hull, a cavity of special shape for constituting the pilot's cockpit, and a double wall on the lower portion of the hull, this double wall forming a water-tight compartment in case of damage at any point of the hull.

125 2. A life boat comprising a hull entirely made of metal, completely water-tight and

in the shape of a frustum of circular cross-section, half-spherical compartments at the bow and stern respectively, three curved transverse channels on the upper plane of this 5 hull, a cavity of special shape for constituting the pilot's cockpit, and a double wall on the lower portion of the hull, this double wall forming a water-tight compartment in case of damage at any point of the hull, an emergency bridge supported by uprights and arranged above the upper plane of the hull, a ladder giving access from the stern of the 10 boat to the said bridge, a tubular mast pivoted at its base on the hull, an electric lighting device supported by the said mast.

3. A life boat comprising a hull entirely made of metal, completely water-tight and in the shape of a frustum of circular cross-section, half-spherical compartments at the 20 bow and stern respectively, three curved transverse channels on the upper plane of this hull, a cavity of special shape for constituting the pilot's cockpit, and a double wall on the lower portion of the hull, this double 25 wall forming a water-tight compartment in case of damage at any point of the hull, three vertical planes secured at the bow of the boat on the half-spherical compartment and on a portion of the length of the hull, a horizontal 30 plane secured at the stern and at the level of the water-line for ensuring stability in case of rolling and acting at the same time as fender, the said vertical planes being moreover utilizable as support for wheels or caterpillars allowing the boat to move and to enter 35 the sea by itself.

4. A life boat comprising a hull entirely made of metal, completely water-tight and in the shape of a frustum of circular cross-section, half-spherical compartments at the bow 40 and stern respectively, three curved transverse channels on the upper plane of this hull, a cavity of special shape for constituting the pilot's cockpit and a double wall on the lower 45 portion of the hull, this double wall forming a water-tight compartment in case of damage at any point of the hull, bulkheads dividing the interior of the hull into four compartments, the first enclosing a second pilot's cockpit, the second constituting the engine-room, 50 the third being reserved for the people rescued and the crew, and the fourth forming a chamber for the people rescued and a store for food, all these compartments communicating with each other and with the exterior 55 through water-tight doors.

5. A life boat comprising a hull entirely made of metal, completely water-tight and in the shape of a frustum of circular cross-section, half-spherical compartments at the bow 60 and stern respectively, three curved transverse channels on the upper plane of this hull, a cavity of special shape for constituting the pilot's cockpit, and a double wall on the lower 65 portion of the hull, this double wall forming

a water-tight compartment in case of damage at any point of the hull, heavy oil or gasoline engines, turbines actuated by these engines, two hydraulic propelling units provided with blades and a fixed casing and mounted in the 70 bottom of the hull, a central water intake for supplying these two hydraulic propelling units, a third hydraulic propelling unit, provided with an adjustable casing and arranged in the longitudinal axis of the hull 75 for ensuring through independent driving members, the steering of the boat.

In witness whereof I have hereunto set my hand.
